UNITED STATES PATENT OFFICE.

SAMUEL FISHER, OF HAMPTON, VIRGINIA.

VENDING-MACHINE.

1,230,375.

Specification of Letters Patent.

Patented Sept. 4, 1917.

Application filed October 13, 1916. Serial No. 125,477.

To all whom it may concern:

Be it known that I, SAMUEL FISHER, a citizen of the United States, residing at Hampton, in the county of Elizabeth City and 5 State of Virginia, have invented new and useful Improvements in Vending-Machines, of which the following is a specification.

This invention comprehends the provision of a vending apparatus, primarily designed 10 for vending perfume, and adapted to be operated by the insertion of a coin of a predetermined denomination, whereupon a certain quantity of perfume is discharged from the apparatus over an article, such as a handkerchief or the like when held in close 15 proximity to the outlet of the apparatus.

The invention further aims to provide a mechanism for registering the number of coins deposited in the machine, the register 20 being connected with the coin controlled element which regulates the discharge of the contents of the machine, and operates simultaneously with the operation of said element.

25 In carrying out the invention I arrange the component parts of the apparatus in such a compact manner, that a comparatively small apparatus is produced which can be conveniently mounted upon the backs 30 of theater seats, railway seats and in other public places.

Another important object of the invention resides in the provision of a coin controlled locking element for the main operating member, which prohibits manipulation 35 of the apparatus by any coin or a substitute therefor, other than one of a size for which the apparatus is designed to accommodate.

The nature and advantages of the invention 40 will be better understood from the following description when taken in connection with the accompanying drawing, the invention residing in the construction, combination and arrangement of parts as claimed.

45 While I have herein stated that the apparatus is primarily intended for dispensing perfume, I desire to have it understood that it is susceptible for use in other capacities and that such general application is contemplated by the claims.

In the drawing forming part of this specification like numerals of reference indicate similar parts in the several views and wherein:

55 Figure 1 is a front elevation of the appa-

ratus constructed in accordance with my invention.

Fig. 2 is a vertical sectional view therethrough.

Fig. 3 is a view showing the cover of the 60 casing open and the arrangement of parts.

Fig. 4 is a horizontal sectional view.

Fig. 5 is a vertical sectional view.

Fig. 6 is a perspective view of the frame 65 and stopper.

Fig. 7 is a similar view of a modified form.

Fig. 8 is an enlarged detail view of the receptacle holder.

Before entering into a detail description of what is herein illustrated I desire to have 70 it understood that the same is merely illustrative of one embodiment of the invention to which I do not limit myself, and that such changes in the construction, combination and arrangement of parts may be resorted to when desired as fall within the 75 scope of what is claimed.

In this particular embodiment of the invention however I make use of a casing 10 which may be constructed from any suitable 80 material, of any size and configuration, but which is preferably of rectangular contour in cross section. The casing is provided with a cover or lid 11 which is preferably 85 hinged to one of the walls of the casing as shown, and which cover may be locked in its closed position in any suitable manner. Extending along the longitudinal center of the cover 11 is a metallic strip 12 having its extremities projecting beyond the ends of 90 the cover and provided with suitable apertures for the reception of suitable fastening elements 13 by means of which the apparatus as a unit can be secured to the backs of theater seats, railway car seats, or any other 95 suitable support where use of the apparatus is found to be desirable. When the apparatus is mounted for use the bottom of the casing constitutes the front wall of the apparatus as clearly shown in Fig. 1. 100

Arranged within the casing 10 and disposed transversely thereof is a receptacle holder 14 which in this particular instance consists of a single strip of metal suitably shaped to support one or more bottles 15 105 in an inverted position in the manner clearly illustrated in Fig. 3. While the holder 14 as shown accommodates but two bottles, I desire to have it understood that the apparatus in its entirely may be of a size to ac- 110

commodate any number of bottles. The holder 14 can also vary in design to accommodate itself to the contour of the particular receptacle which it is adapted to support, as the apparatus is susceptible for use in other capacities than for bottles for the purpose of dispensing perfume. Encircling each of the receptacles adjacent its closed end is a wire annulus 16, the wire forming said annulus being extended and formed to provide a coil spring 17 which is disposed above the bottle as shown. An elongated metallic frame 18 is fitted about each receptacle 15 and mounted for vertical sliding movement through suitable guide grooves provided in the holder 14. The stopper for each receptacle is indicated at 19, and is secured to the lower cross piece 20 of the metallic frame for movement therewith in the manner and for the purpose to be hereinafter described. The coil spring 17 as hereinabove stated is positioned above the receptacle 15 having one end bearing against the latter and its opposite end bearing against the upper cross piece 21 of the metallic frame, and functioning to normally maintain the frame in its elevated position and the stopper 19 in its closed position within its receptacle. The stopper 19 is preferably hollow and perforated one or more times as at 22 depending of course upon the particular quantity of perfume to be distributed at each operation of the apparatus, it being of course understood that when the metallic frame 18 is lowered by the mechanism to be presently described, the stopper 19 is partially removed from the receptacle the requisite distance to permit the contents of the receptacle to flow immediately through the perforations 22. The head of the stopper indicated at 23 is preferably made of rubber so that when the metallic frame 18 and stopper 19 are returned to their normal positions, the head 23 of the stopper will yield to properly seat itself and thus provide a fluid-tight connection with the receptacle.

Journaled within the casing immediately above each of the receptacles 15 is a coin controlled operating wheel 24 which includes a plurality of radially extending blades 25 of suitable length to engage the upper cross piece 21 of the metallic frame and depress the latter as the wheel is rotated. The upper wall 26 of the casing is provided with coin receiving slots 27, the slots being so positioned with respect to the operating wheels 24 that when a coin of the proper denomination is introduced into the casing it will be received within two of the blades 25 of the adjacent wheel. As the coin is moved farther within the casing a rotary motion is imparted to the wheel 24, the latter rotating approximately one-

fourth of a revolution so that the lowermost blade moving over the uppermost cross piece 21 of the metallic frame depresses the latter against the tension of the spring 17, and thereby adjusts the stopper 19 to a position whereby the contents of the receptacle 15 is permitted to discharge therefrom. The receptacles 15 may contain different grades or quantities of perfume, or the perforations in the stopper 19 can vary both in number and size consistent with the quantity of perfume to be discharged for a predetermined sum. In other words one of the receptacles may contain a cheap quality of perfume and the mechanism controlling the discharge of the same designed to be operated by a penny, while the other receptacle or receptacles containing a better quality of perfume may require the insertion of a five cent piece into the apparatus in order to effect a discharge of the perfume from said receptacle or receptacles. These features of the apparatus however are matters of minute importance which are subject to change and variation in accordance with the discretion of the manufacturer or user, and can be so varied without departing from the principle of operation, or the spirit of the invention.

Pivottally mounted within the casing 10 is a substantially L-shaped locking lever, the relatively long branch 28 of which is disposed at one side of the operating wheel and curved longitudinally to normally engage one of the blades 25 thereof, while the relatively short branch 29 of said lever is disposed above the wheel having a portion partly underlying the coin receiving slot 27. The purpose of this lever is to prevent the wheel 24 from being operated by a coin or substitute therefor of different dimensions than the size of the coin for which the apparatus is designed to accommodate. Manifestly when the coin of the proper denomination is inserted within the slot 27 it is brought into contact with the relatively short branch 29 of the lever, imparting a rocking movement to the latter, with the result of moving the relatively long branch 28 out of the path of movement of the wheel, thereby releasing the latter and permitting the same to be rotated on a further movement of the coin. Supported upon the receptacle holder 14 is a coin receiving receptacle into which the coins are deposited when introduced into the casing. Extending across the metallic strip 12 which is mounted upon the cover 11 is a transversely disposed metallic strip 30 having outwardly curved or bulged portions 31 adjacent its opposite extremities which receive a portion of the neck of the receptacles 15 and assist in holding the latter in proper position within the casing when the cover is in its closed position.

In practice a handkerchief or other article may be inserted within the casing through an opening 32 at the lower end of the casing and defined by cutting away of the front wall 33 as shown. A coin of suitable denomination is then introduced into the proper coin receiving slot for the purpose of rotating the wheel 25. As the latter is rotated the requisite distance, the metallic frame 18 is depressed thus lowering the stopper 19 to a position whereby a quantity of the perfume is discharged from the particular receptacle 15 onto the article placed within the casing. As the wheel is moved out of engagement with the frame 18, the coil spring 17 being compressed at the time, expands, during which action of the spring the metallic frame 18 and stopper 19 are returned to normal position. The apparatus in addition to being extremely simple in construction and very compact in its make-up, is very efficient and positive in operation for the purpose intended.

Secured to the inner side of the door 11 and extending transversely ther of is a casing 35 in which is arranged separate series of gears 36, the gears of each series constituting mechanism for registering a number of coins deposited in the machine. The gears of each series are provided with suitable indicia for this purpose. A relatively smaller gear forms the part of each series and is indicated at 37, this gear being fixed upon a shaft 38 which has one end tapered 35 to be received within the groove 39 of the shaft upon which the coin operated wheels are mounted. Manifestly when the coin operating wheels 24 are actuated by the introduction of a coin within the machine the relatively smaller gear 37 of the particular series is actuated, and which in turn actuates the remaining gears of the series for the purpose stated. The front wall of the casing 35 is provided with sight openings 45 39' through which the register may be read.

What is claimed is:—

1. A dispensing apparatus of the character described embodying a receptacle holder, a coin slot in said holder, a receptacle, a stopper for the receptacle, and coin controlled mechanism operable simultaneously with the insertion of a coin within said slot for automatically adjusting the stopper to allow a quantity of the contents of the receptacle to be discharged therefrom.

2. A dispensing apparatus of the character described embodying a receptacle holder, a coin slot in said holder, a receptacle, a hollow perforated stopper therefor, and coin controlled means operable simultaneously with the insertion of a coin within said slot for automatically adjusting the stopper to allow a quantity of the contents of the receptacle to be discharged therefrom through said perforations.

3. A dispensing apparatus of the character described embodying a receptacle holder, a receptacle, a stopper therefor, yieldable means normally holding the stopper fitted within the receptacle, and coin controlled means for automatically adjusting the stopper to a position to allow a quantity of the contents of the receptacle to be discharged therefrom, simultaneously with the introduction of a coin into the holder. 75

4. A dispensing apparatus of the character described embodying a receptacle holder, a receptacle, a hollow perforated stopper therefor, coin controlled means operable simultaneously with the insertion of the coin 80 within the holder for adjusting the stopper to a position to allow a predetermined quantity of the contents of the receptacle to be discharged therefrom through said perforations, and yieldable means for automatically 35 returning the stopper to its normal position at a predetermined interval.

5. A dispensing apparatus of the character described embodying a casing, a closure therefor, a receptacle positioned within the casing, a stopper therefor, and coin controlled means operable simultaneously with the insertion of the coin into the casing for adjusting the stopper to allow a predetermined quantity of the contents of the receptacle to be discharged therefrom. 95

6. A dispensing apparatus of the character described embodying a casing, a closure therefor, a receptacle mounted within the casing, a stopper therefor, yieldable means 100 normally holding the stopper in a closed position, coin controlled means within the casing for automatically adjusting the stopper to a position to allow a predetermined quantity of the contents of the receptacle to be 105 discharged therefrom simultaneously with the insertion of the coin within the casing, and said yieldable means operating to return the stopper to normal position at a predetermined interval. 110

7. A dispensing apparatus of the character described embodying a casing, a closure therefor, a receptacle mounted within the casing, a hollow perforated stopper for said receptacle, coin controlled means for automatically adjusting the stopper to a position to allow a quantity of the contents of the receptacle to be discharged therefrom through said perforation, simultaneously 115 with the insertion of the coin within the casing, and yieldable means operating to automatically return the stopper to its normal closed position at a predetermined interval. 120

8. A dispensing apparatus of the character described embodying a casing, a closure 125 therefor, a receptacle mounted within the casing, a perforated stopper therefor, a coin controlled means for automatically adjusting the stopper to a position to allow a quantity of the contents of the receptacle to 130

be discharged therefrom, said casing being provided with a hand receiving opening at a point beneath said receptacle, and means for automatically returning the stopper to normal position at a predetermined interval.

9. A dispensing apparatus of the character described embodying a casing, a receptacle mounted therein, a perforated stopper for the receptacle, yieldable means normally holding the stopper in closed position, coin controlled means for adjusting the stopper against the tension of said means, to a position to allow a quantity of the contents of the receptacle to be discharged therefrom through said perforations, and means for locking the coin controlled means against fraudulent operations.

10. A dispensing apparatus of the character described embodying a casing, a closure therefor, a receptacle mounted within the casing, a perforated stopper therefor, yieldable means normally holding the stopper in closed position, a coin controlled element mounted within the casing and operable to adjust the stopper against the tension of said yieldable means to a position to allow a quantity of the contents of the receptacle to be discharged therefrom, means for normally locking said element against movement

and actuated by the introduction of coin 30 within the casing, and said yieldable means operating to automatically return the stopper to its closed position at a predetermined interval.

11. A dispensing apparatus of the character described embodying a casing, a receptacle mounted therein, a stopper normally closing said receptacle, coin controlled mechanism for automatically adjusting the stopper to allow a quantity of the contents 40 of the receptacle to be discharged therefrom, said mechanism including an actuating element, means normally holding said element against movement, and said means being released to free said element simultaneously 45 with the introduction of the coin into the casing.

12. A dispensing apparatus of the character described embodying a casing, a receptacle arranged therein, a yieldably mounted 50 yoke straddling the receptacle, a stopper carried by the yoke and normally closing the receptacle, coin controlled means for automatically adjusting said yoke to extract the stopper and allow a quantity of the contents 55 of the receptacle to be discharged therefrom.

In testimony whereof I affix my signature.
SAMUEL FISHER.
